TOY FUNICULAR CAR

Wolfgang Richter, Nuremberg, Germany, assignor to
Ernst Paul Lehmann, Patentwerk, Nuremberg, Ger-
many, a company of Germany

Filed Sept. 7, 1965, Ser. No. 86,869

Claims priority, application Germany Mar. 4, 1965

Term of patent 14 years

(Cl. D34—15)

FIG. 1 is a perspective view upon the front or entrance side of the toy funicular car showing my design;

FIG. 2 is a rear view of the car; and

FIG. 3 is a right side end view of the car.

The characteristic feature of my design resides in the particular configuration of the sliding and supporting members of the claimed car, all as shown in the drawing.

I claim:

The ornamental design for a toy funicular car, as shown and described.
